UNITED STATES PATENT OFFICE.

MARTIN CASTRICUM, OF SPRINGFIELD, MASSACHUSETTS, ASSIGNOR TO THE FISK RUBBER COMPANY, OF CHICOOPEE FALLS, MASSACHUSETTS, A CORPORATION OF MASSACHUSETTS.

MANUFACTURE OF CORD FABRIC.

Application filed May 15, 1922. Serial No. 560,919.

To all whom it may concern:

Be it known that I, MARTIN CASTRICUM, a citizen of the United States of America, residing at Springfield, in the county of Hampden and State of Massachusetts, have invented certain new and useful Improvements in the Manufacture of Cord Fabric, of which the following is a specification.

My present invention relates to the manufacture of cord fabric, in which a plurality of otherwise unconnected parallel cords are embedded in a matrix sheet of rubber.

It has for its object a method and an apparatus whereby the union of the cords and rubber can be accomplished with accuracy and great facility, and with improved control over the spacing of the cords in the composite sheet. It has for a further object the improvement in the manufacture of weftless cord fabric in the additional particulars which will appear from the following description and claims.

My invention will now be described with particular reference to the accompanying drawings, in which—

Fig. 1 is a diagrammatic view illustrating one arrangement of apparatus whereby my invention may be practiced;

Fig. 2 is a top plan view of the apparatus for guiding the cords into contact with the rubber;

Fig. 3 is an end view thereof;

Fig. 4 is a side elevation thereof, showing the parts in position to press the cords against the rubber;

Fig. 5 is a similar view showing the parts in a different position;

Fig. 6 is a fragmentary view of the cord spacing mechanism;

Fig. 7 is an end view of a calender partly broken away, showing the drive for the cord guiding mechanism;

Fig. 8 is a front view thereof;

Fig. 9 is a detail illustrating the manner in which the cords pass through the comb; and

Fig. 10 is a detail illustrating an improved manner of treating the tubes of cord.

The general arrangement of apparatus will first be considered. The preferred manner of supplying the cords 10 is by means of a creel indicated generally by 11, and of a type known in connection with

various forms of textile machinery. Spools or tubes 12, upon which the cord is wound, are supported in the creel by suitable spindles, and are each provided with a friction brake 13, (of which only one has been shown) arranged in a known manner to exert constant individual tension on the cord delivered from each spool. From the creel the cords pass through a guide 14 which arranges them upon a roll 15 in parallel relation. This roll forms one of a group of three, the middle one 16 of which is mounted so as to float in bearing 17 in the frame 18 in which it is supported, so as to exert a yielding pressure on the cords and to grip them so that from this point to the calender the series of cords will act as a unit and fluctuations in tension of individual cords as they come from the creel will be prevented from exerting any appreciable effect when the cords reach the calender. From the last roll 19 of the group the cords pass successively around a series of equalizing rolls 20, which give the cords opportunity to come to equal tensions, under a guide roll 21, and around a series of heating rollers 22, the last of which directs the cords to the adjustable spacing devices which will now be described.

The latter devices, which are illustrated in detail in Figs. 2 to 8, are mounted upon a frame 23 suitably supported on the calender frame 24. The calender comprises three rolls 25, 26, and 27, the upper two of which are adapted to coat to work a feed of rubber 28 into a sheet 29. The cord guiding and spacing devices in the particular embodiment shown are mounted so as to press the cords against the rubber sheet while supported on the center roll 26, although certain features of my invention are equally applicable in cases where the cords are guided against the bare lower roll 27, as in my prior application Serial No. 394,566 filed July 7, 1920, or are guided to the rubber at any other desired point. The guiding devices comprise a series of rods or wires 30 adjustably mounted as will be described, a fixed bar 31 under which the cords pass, and a roller 32 preferably smooth-surfaced and also preferably positively driven at a surface speed slightly less than that of the sheet of rubber. These parts are mounted in carriages 33 slidable in ways 34 on the

frame 23, and having screw-threaded apertures into which fit screws 35 secured against axial movement in upwardly extending portions 36 of the frame 23. A shaft 37 passes between the portions 36 and carries a handwheel 38 by which it may be rotated. Worms 39 on the shaft mesh with worm wheels 40 on the screws 35. By rotating the handwheel, the cord guiding devices can be moved towards or away from the calender roll, the extreme positions being indicated in Figs. 4 and 5. The purpose of this adjustment will be discussed in detail in connection with the method of operating the apparatus.

The adjustable comb, composed of the wires or rods 30 which guide the cords to the bar 31 and space them thereon, is shown as of a general type such as has been used in certain types of textile machinery, and its detailed description may be somewhat abbreviated for that reason. The combination of this general type of comb and the other parts of the apparatus, however, performs novel functions not present in or suggested by the use in textile machinery, and I desire to claim that combination in both its broad and specific forms. The rods 30 have holes therein through which pass wires 42 secured in a box 43 fastened between carriages 33. Also slidable on the wires 42 are blocks 44 having attached thereto two sets of interlocking helical springs 45 threaded around the rods 30. A screw 46, having right and left hand threads engaging the two blocks respectively, passes between the ends of the box and is provided with a handle 47 by which it may be rotated. Turning of screw 46 will result in a separation or a bringing together of the two blocks, with a consequent stretching or compression of the helical springs. As the springs are interlaced with the rods, the latter will be uniformly spaced at intervals varying according to the stretch given to the springs. Consequently, by turning handle 47 the spacing of the cords as they reach bar 31 may be varied without any necessity of disturbing or restringing the cords, and even while the cords are traveling. Although this form of adjustable comb will be found very convenient in accomplishing the results desired, I do not wish to limit myself thereto, as other specific forms may be substituted in its place without departing from the invention.

A convenient manner of driving the roll 32 at the desired peripheral speed in exact relation to the calender is illustrated in Figs. 7 and 8. In these figures the roll has been shown connected to the lower roll of the calender, which, by reason of its being geared to the other calender rolls, will drive the roll 32 at a peripheral speed having an

exact relation to the surface speed of the 65 rubber sheet on the middle calender roll. As shown, the lower calender roll shaft is provided with a sprocket 50 connected by a chain 51 to a sprocket 52 freely rotatable on an idler shaft 53. A clutch portion 54, 70 formed integrally with sprocket 52, is adapted to cooperate with a similar clutch portion 55 keyed to the shaft and movable back and forth by means of a handle 56 in a manner customary with clutches of this general 75 type. A sprocket 57 fast to shaft 53 is connected by a chain 58 to a sprocket 59 fast on the shaft 60 of roll 32. By this means the roller 32 can be driven or stopped as desired, its driven speed being in constant 80 proportion to the calender speed. As previously stated, the roll 32 is preferably so geared that it travels at a peripheral speed slightly less than the speed with which the rubber and cords are carried by the calender. 85 This gives a slight ironing action, keeping the cords taut and assisting in maintaining them in their proper positions.

The preferred manner of delivering the composite sheet from the calender and trimming its edge portions embraces knives 65 mounted on suitable supports adjacent roll 26 in a manner known in the art of operating calenders (see, for example, the patent to Lewis 1,151,527, August 24, 1915), and set 95 so as to cut the rubber at each side of the series of cords. Beyond the knives is an idler roller 66 preferably smaller than the roll 26, and over which the trimmed composite sheet of cord fabric 67 passes, the 100 marginal portions of rubber passing on roll 26 back into feed 28. This directing of the sheet and the marginal portions along abruptly diverging paths insures accurate trimming and reduces to a minimum both 105 the stretching of the rubber with which the cords are coated and the consequent curling of the edges of the fabric.

A convenient and preferred manner of mounting the tubes of cords to assist in the 110 continuous operation of the apparatus will now be described. This mounting, and the manner of handling, has particular utility when used with the devices previously described, and certain additional features of 115 those devices will be considered in this connection. It is preferable to arrange the cords as shown in Fig. 9 in groups of three or four in each "dent" between adjacent rods 30 of the comb, the bar 31, which exerts a 120 sliding friction on the cords, serving to arrange the cords in a sheet of uniform spacing. This construction avoids the necessity of having a comb of extreme fineness, which adds cost and complexity and also provides 125 space which permits of the passage of knots in the cords. It is desirable to operate the calender continuously until the desired

amount of cord fabric has been produced. If it is necessary to stop the calender and restring all the cords after the tubes 12 have become exhausted, much time will be consumed and, if the rubber stock is left on the calender during the restringing period, the rubber will lose its proper condition of plasticity and much scrap will result. By so arranging the comb that ample space is provided for knots to travel through, the tubes of cord may be spliced and replaced while the calender is operating.

In order not to have all the knots come at one place in the composite sheet, and to facilitate the work of the operator in splicing the large number of tubes mounted on the creel, I preferably arrange the tubes initially so that they have varying lengths of cord on the several tubes, conveniently in regular progression from one extreme of the creel to the other. This has been indicated diagrammatically in Fig. 1 by the difference in diameters of the various tubes. The tubes in the horizontal rows are indicated as being of substantially uniform size, but it will be understood that all the tubes are preferably arranged in a regular progression. The operator can with this arrangement work from one section of the creel to the other, replacing with full tubes the ones that become empty, and tying to the last end of the cord from an emptied tube the leading end of the cord from a full tube. As the full tubes are supplied with substantially uniform lengths of cord wound thereon the order in which the tubes become empty will remain the same after the initial setting-up, and the creel requires no attention other than the progressive replacement of the tubes as they run out.

Another feature of my invention by which I insure regularity in the operation of the apparatus is illustrated in Fig. 10. The cord is supplied wound in so-called tubes 12 on a core 70, the cord being wound helically back and forth on the core in a manner as to build up a tube containing a very great length of cord. As the cord is withdrawn from the tube as the latter is in use on the creel, the cord is at regular intervals drawn off from points 71 at the edge of the tube. Sometimes the cord at this point will slip down the end of the tube particularly if the tube has been subjected to rough handling before mounting in the creel, with consequent unevenness of feed and inequality of tension, even resulting at times in binding and breaking of the cord. To avoid this difficulty without interfering with the rubber coating operation, I preferably coat the ends 72 of the tube of cords with an adhesive sufficiently firm to prevent the cords slipping over the end of the tube and yet permitting their being drawn off as required

by the calender operation. It will in most instances be found sufficient if the coating is applied only around the outer corners of the tube and a short distance down the ends. This adhesive is of a nature which will not affect the adhesion to the cords of the later applied rubber, and may conveniently be composed of rubber cement. If this cement is applied to the ends of the tubes after the latter have been wound it will protect them in handling and prevent breakage of cords in operating the calender.

If a wide range of adjustment of the spacing of the cords is desired, a second adjustable comb 75 may be placed adjacent guide roll 21. This may be of the same type as comb 30, or, as indicated diagrammatically in Fig. 1, of the so-called "saw-tooth" type of comb in which the pins are mounted in a zig-zag line along the links of a lazy-tongs, by the stretching or contracting of which the spacing may be adjusted. This type of comb is also known in various textile devices, and needs no extended discussion here as to the details of its construction. The provision of this second comb breaks up the variation in spacing between guide 14 and the calender into two sections, and gives more accurate control than in case a single comb only were used.

The composite sheet 67 resulting from the first coating operation is delivered from roll 66 to a wind-up drum 80, preferably power driven as is customary with calender wind-up devices, and mounted so that it will not have any endwise motion. A liner 81 is fed under tension from a spool 82 between the convolutions of the cord fabric sheet on the drum 80 so as to prevent the adjacent turns sticking together. After all the material has been run that is desired, or that can conveniently be mounted on drum 80, the sheet is severed, and the cords tied back as previously described. The calender is now made ready to deliver stock of the gauge and quality desired for the second coat. For this second coating operation, the partially finished sheet 67 is led from drum 80 under the bottom calender roll 27, around a guide roll 83, and between the two bottom calender rolls, where it is pressed against a rubber sheet formed by the upper pair of rolls. The finished sheet, indicated by 84 in Fig. 1, is led around roll 66 and delivered to any suitable wind-up device. The liner 81 is during this operation rerolled upon roll 82, which may be actuated by any suitable wind-up device.

It will be noted that the registration of sheet 67 with the calender is never disturbed during the two calendering operations, and that no resetting of the drum 80 is required. In this manner the sheet 67 will be delivered to the second coating operation in a definite

position, to which the knives 65 can be readily accommodated, insuring accuracy in trimming.

device positioned to arrange the series of records in parallel relation on said roll, and means for adjusting the device to vary the

Having thus described my invention, I am ~~desirous~~ to have the spacing of the cords.

DISCLAIMER

1,500,232.—*Martin Castricum, Springfield, Mass. MANUFACTURE OF CORD FABRIC.* Patent dated July 8, 1924. Disclaimer filed November 21, 1936, by the assignee, *The Fisk Rubber Corporation*

Hereby enters this disclaimer to claims 1, 3, and 4 of the specification.
